CHICK BOX SPACING CONSTRUCTION

Norbert F. Schaefer, Indianapolis, Ind., assignor
to Anderson Box Company, Indianapolis, Ind.,
a corporation

Application December 14, 1938, Serial No. 245,590

4 Claims. (Cl. 229—6)

This invention relates to the spacing of stacked chick boxes, the purpose therefor being to ventilate through the cover, the lower and supporting box. For such purpose the cover is suitably apertured as well understood in the art, hence the same is neither illustrated herein, for clearness, nor will the same be more specifically referred to hereinafter.

The chief object of the present invention is to provide spacing means at each corner of a chick box and centrally thereof if, as and when desired, so that cross-ventilation may be effected above the cover between boxes.

The chief feature of the invention resides in providing a spacer which may be readily applied to a standard cover and secured thereto without stapling or gluing by merely appropriately slotting the cover.

Other objects and features of the invention will be set forth more fully hereinafter.

The full nature of the invention will be understood from the accompanying drawing and the following description and claims.

In the drawing:

Fig. 1 is a perspective view of a plurality of chick boxes in stacked relation.

Fig. 2 is a top plan view of a chick box cover structure with two specific embodiments of the invention applied thereto, and two of the corner spacers being omitted to illustrate two different types of spacer mounting.

Fig. 3 is a developed plan view of corner spacer shown in Fig. 2 and the one adapted for mounting in the upper right hand corner of the cover shown in Fig. 2.

Fig. 4 is a view similar to Fig. 2 but of a different embodiment of the invention.

Fig. 4—A is an enlarged sectional view of the embodiment shown in Fig. 4 taken in a plane substantially coincident with the top surface of the cover.

Fig. 5 is a developed plan view of the spacers shown in Fig. 4 and adapted for mounting in the lower right hand corner of the cover shown in Fig. 4.

Fig. 6 is a developed plan view of a corner spacer similar to that shown in Fig. 5 and adapted for mounting in the upper right hand corner of the cover shown in Fig. 4.

Fig. 7 is an enlarged plan view of a modified form of spacer, and the adjacent cover corner portion.

Fig. 8 is a developed plan view of the blank forming the spacer shown in Fig. 7.

Fig. 9 is a transverse sectional view taken on line 9—9 of Fig. 7 and in the direction of the arrows.

In the drawing 10 indicates a box bottom and 11 indicates a cover having a depending bottom telescoping rim 12 in Fig. 1 the usual transverse partitions in the box bottoms are internally omitted. They may take any one of many forms. Likewise, the usual apertures in the side and end walls as well as the top of the cover intentionally have been omitted for clearness from both boxes in Fig. 1 and all other figures as well.

Fig. 1, as stated, shows two boxes, one being stacked upon the other, the upper box bearing 15 on suitable spacers secured to the cover of the lower box and indicated generally by the numeral 13. If, as and when desired, a central spacing member also may be employed. It is, of course, to be understood that all spacers have a co-planar top supporting surface arrangement 20 so that the bottom body portion of the superposed container or chick box will be supported in parallel relation to the lid or cover of the lower box bottom.

The advantage of the aforesaid spacing are 25 that air can freely circulate between the two boxes from either of the transverse directions or angularly of the two transverse directions, thereby insuring free passage of air between two boxes, even if the stack be positioned against a blank 30 wall or in a corner of a compartment, etc.

Reference will first be had to Fig. 2 wherein 35 the cover structure is shown adapted to support a spacer of triangular outline at each corner, two being shown in Fig. 2 as actually applied to the cover. These triangular spacers, as shown positioned so that the base portion thereof extends from one side edge to an adjacent side edge of the cover and, as illustrated in Fig. 2, each projects a slight distance therebeyond, as indicated at 14. The base face or wall of the triangular spacer is indicated by the numeral 15. The two other sides are indicated by the numeral 16 and the vertex is indicated by the numeral 17. This vertex is positioned between the triangle base 15 and the central portion of the cover herein and the triangular spacer has all of the sides 15 and 16 suitably connected together by a triangular shaped bearing portion 18. Thus there is 40 provided an appreciable bearing area for superposed box support.

Furthermore, when four corners spacers are utilized, as well as when the same and a fifth central spacer are utilized, if the boxes be slightly 45 50 55

misaligned when in stacked relation, they nevertheless will be supported in parallel and spaced relation. In other words, one corner of a box will not sag toward or bear directly upon the immediately adjacent cover, thus throwing out of parallelism the superposed boxes, if any, and the initial non-parallel superposed box. The central spacer prevents central or intermediate sagging.

These projecting portions 14 may serve to space the box from an adjacent wall and from adjacent boxes in the same co-planar relationship, and this occurs even though the stacks or tiers of boxes be slightly off-set because then the projecting portions 14, having the same co-planar relationship, will inter-fit, as it were. This insures vertical ventilation along the sides of the stack of boxes for side wall ventilation of the boxes.

A preferred form of anchoring each of the corner spacers embodying the invention is by a tongue and slot connection, in each instance the slots being formed in the cover and the tongues being formed on and as an integral part of the spacer structure. As shown in Fig. 2 in the upper right hand corner the cover is provided with two diverging spaced slots 19 and two aligned slots 20. The triangular spacer structure shown in Fig. 3 has each wall 16 provided with a T-shaped tongue 21, each tongue being receivable by a slot 19 and lockingly associated with the cover 11 by reason of the enlarged portion 21a. Portion 15 of the triangular spacer shown in Fig. 3 is provided with a plurality of locking tongue portions 22 enlarged as at 22a to provide a T-shaped formation. Each tongue 22 is received by a slot 20, see Fig. 2, for lockingly securing the spacer to the cover.

If the portion 15 of the triangular spacer shown in Fig. 3 were provided with one locking projection or tongue 22-22a the same preferably would be medianly positioned and then that spacer, as thus modified, could be mounted in the same manner by associating the tongues 21 and 22 with the cover slots 19a and 20a shown in the lower right hand corner of Fig. 2.

If desired, the tongue and slot connection may readily be reversed. In this instance tongues will be struck up from the cover and interlock in slots formed in the spacers, or separators, without departing from the basic invention.

In Fig. 2, the two transverse dotted lines 23 indicate the position relative to the cover which transversely positioned partitions assume when the cover is mounted upon a partitioned chick box structure.

It will, of course, be obvious that the triangular spacer shown in Fig. 3, or the modified form thereof described, may be associated with the cover and applied to the central position thereof. In the present invention a central spacer can not be shown applied to cover 11, see Fig. 1, because of the angle of the perspective in which Fig. 1 is taken.

Herein this central spacer, see Fig. 2, may be considered of dual triangular type, in other words, diamond shaped, and the points thereof are in alignment with the transverse partitions. Such a spacer includes a top surface forming portion 24 and four side wall portions 25 hingedly connected thereto and directed toward the cover portion. Extending in co-planar relation with said side wall portions 25 are the locking tongues 26, each tongue being preferably of T-shaped character and receivable by a slot 27 provided in

said cover. As stated, all of the surfaces 18 of the corner spacers and the surface 24 of the central spacer are co-planar.

Since in most chick boxes the height of the partitions 23 are substantially the same as the height of the side and end walls of the box structure, and since the body portion 11 of the cover bears thereon it will be noted that the load of the superposed box, or boxes, in the stack is transmitted to the supporting box or lower box 10 through the spacers, cover, partitions and side and end walls. Thus, in effect, the weight of the stack is carried through the side and end walls and through the transverse partitions if, as and when the central spacer is employed.

It will be noted also, see Fig. 2, that the tongue portions 26 lie in the "corner" between the transverse partitions and thus do not interfere with the transverse partitions in the seating of the cover.

In Figs. 4 to 6 there is illustrated a modified form of the invention which may be of single tongue or plural locking tongue type, compare Figs. 5 and 6. In these figures numerals of the 100 series similar to the primary numerals previously employed herein designate like or similar parts, as designated by numerals of the primary series. In this form of the invention also, the triangular outline is shown substantially equilateral, whereas the triangular outline of the spacer shown in Figs. 2 and 3 is isosceles in character. Herein a central spacing member is shown having four sides and square in outline.

This form of the invention differs from that illustrated in Figs. 1, 2 and 3, in that the bearing area instead of comprising a triangular or diamond shaped surface constitutes a bearing area of triangular or square outline, the upper edges of the sides being co-planar. In other words, the spacing structure is tubular in character.

As illustrated in Fig. 5, there are three portions 116 hingedly connected together as at 116a and provided with the upper edge 118. Each is provided with a depending tongue 121 at its opposite edge and medianly positioned relative to portion 116. This tongue is of T-shaped character having a lateral enlargement 121a. The cover, see Fig. 4, is provided with three triangular arranged openings 119 and these lockingly receive tongues 121 for lockingly connecting the tubular triangular structure to the cover.

Preferably the two hinge portions 116a are positioned at or adjacent the adjacent edges of the cover and the disconnected edges 116b are positioned adjacent each other and at the vertex of the tubular triangular spacer, the vertex being positioned between the base face portion which extends across the corner, as it were, and the central portion of the cover.

These portions 116a are herein shown positioned within the outline of the side edges of the cover. They may, however, be positioned so that they project beyond the sides or rim portions of the cover, as indicated at 14 in Fig. 2.

In Fig. 6 there is illustrated a slightly modified form of this structure. The same numeral 116 indicates the same three sections or side walls. These are hingedly connected together at 116a. The ends of the blank are indicated by the numeral 116b. However, in this specific variation of the embodiment of the invention shown in Figs. 4 to 6, inclusive, each side wall portion 116b is provided with a plurality of co-planar and depending integral locking tongues 121, each being

T-shaped and having the lateral enlargement 121a.

The cover 111 in the upper right hand corner is shown provided with three pairs of slots 119a 5 triangularly arranged, as shown.

Herein, see Figs. 4 and 4-A, the transverse dotted lines indicate two transverse partitions 123, or rather the position same would occupy relative to the cover when the cover is applied to 10 a transversely partitioned box bottom structure.

Herein, see Fig. 4, the central spacing member includes four side walls 125, each having the upper edge 124 and these four edges of these four sides 125 are co-planar and co-planar with the 15 top edges 110 of the four triangular corner spacers.

As illustrated in Figs. 4 and 4-A integral with each of the side walls 125, and herein integral with an adjacent wall, is a locking tongue structure that when the side walls are arranged in peripheral and quadrilateral outline form an angular sectioned locking tongue 126 receivable by the angular slot 127 in the cover 111. Thus the locking tongues 126 may at each side edge 20 form a locking projection. The arrangement thereof also is such that the locking tongues 126 do not offer an obstruction to the seating of the cover upon the top edge of the transverse partitions 123 and the top edges of the side and end 25 walls of the box bottom structure.

It is, of course, to be understood that all of the lateral projections of the tongues previously mentioned underlie the under face of the supporting cover and the shape of said enlargement 30 may be such, if desired, that after the tongue portion is passed into and through the slot the locking enlargement yieldingly draws the side wall supporting the same into relatively close contact with the upper surface of the adjacent 35 cover portion.

Reference will now be had to Figs. 7 to 9, inclusive. In these figures numerals of the two hundred series indicate like or similar parts. Thus 211 indicates the body portion of the cover 40 and 212 the rim thereof. The cover is provided with spaced corner biased slots 219. A corner spacing member includes the top surface portion 218 parallel to the cover 211 and the same may 45 and herein is shown projecting beyond the rim 50 portion as at 214. One side wall 215 extends from one side edge to the adjacent side of the cover.

Another side wall 216 is provided and herein is shown positioned parallel to the side wall portion 215. Integral with the side wall 215 is the locking tongue 222 having the enlarged portion 222a, the projection being T-shaped in outline. Similarly the wall 216 is provided with a corresponding T-shaped locking projection 221 enlarged as at 221a.

Integral with each of the portions 215 and 216 are the L-shaped portions 240 and 241. These, as shown in Fig. 8, partially embrace, as it were, the adjacent locking tongues. When the blank 65 shown in Fig. 8 is assembled together with the tongue 240a and the tongue 241a of the angular portions interlock, as shown in Fig. 9. Thus there is provided a semi-tubular type structure which is X-braced, as it were.

The type of spacer shown in Fig. 7 also may be 70 centrally positioned and when its longitudinal direction coincides with a diagonal of the cover the slots 219 will lie parallel to each other upon opposite sides of the cover center and the diagonal 75 mentioned and the tongues when mounted in the

central slots will be in non-interfering relation for cover seating and with respect to the transverse partitions if embodied in the box structure.

The invention claimed is:

1. A box cover structure for spaced stackable chick boxes including a quadrilaterally outlined cover and spacing means at each corner and each including three sides arranged in triangular outline, each of the sides having an upper edge substantially coplanar with all other side edges, each 10 triangular spacing means being formed from a single piece of stock, the said sides constituting marginal extensions of a triangular body portion forming a triangular bearing area for a superposed box. 15

2. A box cover structure for spaced stackable chick boxes including a quadrilaterally outlined cover and spacing means at each corner and each including three sides arranged in triangular outline, each of the sides having an upper edge substantially coplanar with all other side edges, each 20 triangular spacing means being formed from a single piece of stock, the said sides constituting marginal extensions of a triangular body portion forming a triangular bearing area for a superposed box, the cover being suitably apertured adjacent each spacing means and in alignment with the sides thereof, and locking means on the lower edge of each side and positioned for cover aperture reception for spacing means connection 25 to cover. 30

3. A box cover structure for spaced stackable chick boxes including a quadrilaterally outlined cover and spacing means at each corner and each including three sides arranged in triangular outline, a vertex of the triangular outline being positioned between the cover adjacent corner and the cover center, the other two vertices of the triangular outline being positioned between the first mentioned vertex and the said adjacent corner 35 and spaced therefrom, the second mentioned vertices being at opposite sides of a plane transverse to the cover structure and including the first mentioned vertex and adjacent corner, each of the sides having an upper edge substantially coplanar with all other side edges, each triangular 40 spacing means being formed from a single piece of stock, the said sides constituting marginal extensions of a triangular body portion forming a triangular bearing area for a superposed box. 45

4. A box cover structure for spaced stackable chick boxes including a quadrilaterally outlined cover and spacing means at each corner and each including three sides arranged in triangular outline, a vertex of the triangular outline being positioned between the cover adjacent corner and the cover center, the other two vertices of the triangular outline being positioned between the first mentioned vertex and the said adjacent corner and spaced therefrom, the second mentioned vertices being at opposite sides of a plane transverse to the cover structure and including the first mentioned vertex and adjacent corner, each of the sides having an upper edge substantially coplanar with all other side edges, each triangular 65 spacing means being formed from a single piece of stock, the said sides constituting marginal extensions of a triangular body portion forming a triangular bearing area for a superposed box, the cover being suitably apertured adjacent each 70 spacing means and in alignment with the sides thereof, and locking means on the lower edge of each side and positioned for cover aperture reception for spacing means connection to cover. 75
